HANS FRÖHLICH AND RICCARD PUDELKO, OF ZUG, SWITZERLAND, ASSIGNEES TO
LANDIS & GYR, A.G., A JOINT-STOCK COMPANY OF SWITZERLAND

INDUCTION METER

Application filed July 19, 1928, Serial No. 293,940, and in Switzerland September 24, 1927.

The invention relates to novel and useful improvements in induction meters, and more particularly to such improvements in the construction and positional regulation of the electro-magnetic driving elements and electro-magnetic connections therebetween.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:
Fig. 1 is an elevation, with parts omitted, of a meter mechanism embodying the invention;

Fig. 2 is a top plan corresponding to Fig. 1, with certain parts omitted;

Fig. 3 is an elevation of a modified embodiment, with certain parts omitted; and

Fig. 4 is a similar elevation, of another modified embodiment of the invention.

The invention is directed to improvements in the type of induction meters wherein the magnet cores of the driving system, for example, the pressure and current cores, are connected together by a ferro-magnetic metal connection, constituting a magnetic shunt, usually consisting of plates or laminæ of iron uniting the driving magnet cores, which are the same or similar to the plates or laminæ of the core, and which are frequently made integral with the core. In induction meters of this type, having connections such as described, the reluctances of the paths of the effective driving fluxes are reduced, and thus

with a smaller number of ampere terms of excitation, comparatively larger fluxes are obtained and thereby proportionately larger torque or rotative effect from the fluxes is secured.

The present invention is directed to improvements in the construction, arrangement and mounting of the parts of the driving system of the kind described, whereby great facility and ease in the assembling of the parts is obtained, any subsequent changes or replacements of parts are quickly and easily effected; and concomitantly therewith relative adjustment of the driving magnets and their part are very quickly and easily effected, without disturbing the operation of the electro-magnetic shunt path. In meters having driving systems of the type described, and wherein the shunt path elements are formed of a single piece, or of a group of plates or lamella, the assembling of the instrument is rendered complicated, difficult and expensive, since the individual lamella to constitute the laminated iron core must be arranged in layers within the coils, or the coils must be wound by hand on the finished laminated iron core. Furthermore, even with coils in which the lamellæ are arranged in layers, any exchange or replacement of parts, such as would be required by reason of a defect in a coil is not possible.

Simply constructing the various core and shunt elements in separate parts, while it facilitates the assembling of the parts, presents serious practical difficulties in that it is difficult or well nigh impossible to effect accurate relative adjustment of the core elements with respect to each other and to the meter disc. By the present invention, we provide a multi-part core and magnetic shunt structure together with means and devices whereby these may be accurately positioned and uniformly and accurately adjusted with respect to the driven meter elements and to each other with

out disturbing the operation of the shunt connection.

Referring now in detail to the exemplary embodiment of Figs. 1 and 2, a frame 1 is shown on which a pressure core 2 is mounted. In this embodiment the pressure core has three arms, 3, 4 and 5, which are substantially parallel, the pressure coil 5 being mounted on the central arm 4. The terminal pole of the arm 4 is preferably laterally extended in both directions as shown at 6, and constitutes an enlarged pole terminal for the pressure flux and also provides air gaps between this pole and the opposite sign pressure poles at either side.

The meter disc 13 is mounted on a spindle 14, which is journaled at its bottom end in a screw-threaded bearing 15, mounted in a bracket 16, carried on the meter frame 1. At its upper end, the spindle 14 is journaled in a screw-threaded bearing 19 supported in a bracket 20, which is likewise carried on the meter frame 1. A worm 21 on the spindle serves to drive a register of any known or other suitable form.

The embodied form of current magnet comprises arms 27 and 28 constituting opposite poles, and mounted on these arms are current coils 29 and 30, these arms being connected together by the central transverse part 31 of the core. The magnetic shunt path in this embodiment is provided by arms or extensions 35 and 36 integral with and extending from either side of the current core and preferably integral therewith, these arms extending upwardly and terminating in faces 37 and 38 in close sliding contact with corresponding faces 39 and 40, formed on the outer sides of the ends of the core terminals 3 and 5 of the pressure magnet. These contacting and magnetically conducting faces are preferably arranged parallel to the axis of the meter spindle.

In the embodied form of supporting and positioning means, bolts 45 and 46 are mounted in apertures in the meter frame 1 and extend through apertures in the lower ends of the pressure core arms 3 and 5, and nuts 47 and 48 are screw-threaded on the bolts to support and to hold the core in place. The bolts 45 and 46 are also utilized to support the magnet positioning means, and as embodied, there are interposed between the pressure core and the frame bell-crank levers 49 and 50, which are pivotally mounted on the respective supporting bolts 45 and 46. Into the outer ends of the horizontally-extending arms of the bell-crank levers are screwed, respectively, screws 51 and 52, upon which the arms 35 and 36 of the current core construction are pivotally supported.

To provide fine and accurate positioning means, differential screws 55 and 56 are screw-threaded into the respective side flanges of the meter frame 1, the inner ends of these

screws passing through apertures in the downwardly-extending arms 57 and 58 of the bell-crank levers. The heads of these screws on the far sides of the two lever arms are beveled or rounded, and the apertures in the arms are shortened and are correspondingly shaped, so as to prevent binding at any position in the small range of movement of the arms. For the purpose of firmly clamping the arms, and consequently the electro-magnetic driving elements in any desired position, clamping screws 59 and 60 are screw-threaded into the lower ends of the bell-crank levers, respectively, and may be screwed tightly against the frame plate 1, to clamp the parts in position, and may be slightly unscrewed to permit movement of the parts during the positioning operation.

In the modified embodiment of Fig. 3, a pressure magnet is shown having three arms 65, 66 and 67, the pressure coil 68 being mounted upon the central arm. The outer arms 65 and 67 of the core are shown with lateral extensions 69 and 70 extending toward the pole terminal of the central arm 66, of the core. The current magnet is shown with a core having two arms 71 and 72 and corresponding poles, the current coils 73 and 74 being carried upon these two arms.

The shunt path connections in this form are likewise constituted by arms 75 and 76, extending outwardly and upwardly at either side of the current magnet, and terminating in faces 77 and 78 which are in close contact with similar faces 79 and 80 on the outer sides of the terminals of the arms 65 and 67 of the pressure magnet, these contacting faces being preferably parallel to the axis of the meter spindle. These contacting terminals 79 and 80 of the pressure magnet core arms 77 and 78 and of the shunt path arms 75 and 76, are provided with alined complementary recesses 83 and 84. One of the magnets, at least, and if desired both, are provided with supporting means, which are movable and clampable in different positions, as for instance, the current magnet may have bolt and slot connections 85 and 86 with the frame plate 1. By inserting a screw driver, or other suitable implement in the slots 83 and 84 (as indicated at the left hand side of Fig. 3), and slightly rotating same in either direction, a nice and accurate adjustment of the magnet terminals with respect to each other and with respect to the meter disc or other driving elements, may be effected, the supports being very slightly loosened preparatory to such movement and being tightened thereafter to clamp the magnets in the desired position.

In the embodiment of Fig. 4, a pressure magnet is shown having a central arm 91 and side arms 92 and 93, the pressure coil 94 being wound on the central arm. The lower parts of the arms 92 and 93 of the core have

extensions 94 and 95 extending inwardly toward the pole terminal of the central arm 91 of the pressure core.

The current magnet has a core with a central arm 97 and parallel outer arms 98 and 99, upon which are carried the current windings 100 and 101. The magnetic shunt in this construction comprises downwardly extending arms 103 and 104, integral with the 10 arms 92 and 93 of the pressure core, and corresponding outwardly and laterally extending arms 105 and 106, integral with the 15 current core. The arms 103 and 104 terminate in contact faces 109 and 110, and in sliding contact therewith are contact faces 111 and 112 formed on the arms 105 and 106, these faces being preferably parallel to the axis of the meter spindle. The embodied form of positioning means in this structure comprises 20 pairs of plates 115 and 116 attached by pins 120 at either side to the arms 103 and 104 (the front left-hand plate in Fig. 4 being omitted). These pairs of plates serve as guides on either side, and at either end, of the 25 arms 105 and 106. Screws 117 are screw-threaded into the plates 115 and 116 respectively and these screws carry affixed thereto eccentrics 118, which work in apertures 119 in the respective arms 105 and 106. By turning 30 the screw-bolts 117 the magnets may be variably positioned with respect to each other. The pressure core is preferably supported on the frame of the meter by suitable means such as screws in the apertures 119. It will be 35 clear that the various forms of positioning means may be employed with the different forms of core arms and mountings.

The invention in its broader aspects is not limited to the specific mechanisms shown 40 and described but departures may be made therefrom within the scope of the accompanying claims without departing from the principles of the invention and without sacrificing its chief advantages.

45 What we claim is:—

1. An induction meter including in combination a driven meter member, driving means therefor comprising a plurality of co-operating electro-magnets, and connection 50 between the cores of said electro-magnets consisting of ferro-magnetic metal and means for variably positioning said cores without breaking said connection.

2. An induction meter including in combination a driven meter member, driving means therefor comprising a plurality of co-operating electro-magnets, and connection 55 between the cores of said electro-magnets consisting of ferro-magnetic metal, means for variably positioning said cores without breaking said connection and means for holding 60 a core in a desired position.

3. An induction meter including in combination a driven meter member, driving means 65 therefor comprising voltage and current coils

and cores, and connection between said cores comprising members having faces in contact, and means for moving one of the cores while maintaining said faces in contact.

4. An induction meter including in combination a driven meter member, driving means therefor comprising a plurality of co-operating electro-magnets, and connection between the cores of said electro-magnets comprising a member magnetically connected to the core 70 of one magnet, a member magnetically connected to the core of another magnet, said members having contacting faces, and means for moving one of said magnets while maintaining said faces in contact. 75

5. An induction meter including in combination a driven meter member, driving means therefor comprising a plurality of co-operating electro-magnets, and connection between the cores of said electro-magnets 80 consisting of ferro-magnetic metal, means for variably positioning said cores without breaking said connection and screw-threaded means for movably positioning one magnet with respect to another. 85

6. An induction meter including in combination a driven meter member, driving means therefor comprising a plurality of co-operating electro-magnets, and connection between the cores of said electro-magnets 90 comprising members having faces in contact, means for moving one of the magnets while maintaining said faces in contact and means for holding a core in a desired position. 95

7. An induction meter including in combination a driven meter member, driving means therefor comprising a plurality of co-operating electro-magnets, and connection between the cores of said electro-magnets 100 comprising members having faces in contact, means for moving one of the magnets while maintaining said faces in contact and screw-threaded means for movably positioning one magnet with respect to another. 105

8. An induction meter including in combination a driven meter member, driving means therefor comprising a plurality of co-operating electro-magnets, and connection between the cores of said electro-magnets comprising a member magnetically connected to the core of one magnet, a member magnetically connected to the core of another magnet, said members having contacting faces, means for moving one of said magnets while maintaining said faces in contact and means for holding a core in a desired position. 115

9. An induction meter including in combination a driven meter member, driving means therefor comprising a plurality of co-operating electro-magnets, and connection between the cores of said electro-magnets comprising a member magnetically connected to the core of one magnet, a member magnetically connected to the core of another. 125

magnet, said members having contacting faces, means for moving one of said magnets while maintaining said faces in contact and screw-threaded means for movably positioning one magnet with respect to another.

5 10. An induction meter including in combination a driven meter member, a voltage coil and core, a separate and distinct current coil and core, a ferro-magnetic connecting member connecting said cores and means for 10 variably positioning said cores while maintaining the connection between said cores.

In testimony whereof, we have signed our names to this specification.
